UNITED STATES PATENT OFFICE.

LOUIS F. HESS, OF ANSTED, WEST VIRGINIA, ASSIGNOR OF ONE-HALF TO WILLIAM N. PAGE, OF ANSTED, WEST VIRGINIA.

MINING-MACHINE.

1,032,902.

Specification of Letters Patent. Patented July 16, 1912.

Application filed October 18, 1911. Serial No. 655,336.

To all whom it may concern:

Be it known that I, LOUIS F. HESS, a citizen of the United States, residing at Ansted, in the county of Fayette and State of West Virginia, have invented a new and useful Mining-Machine, of which the following is a specification.

The device forming the subject-matter of this application, is a mining machine, adapted primarily for operation upon coal, the machine being of that general type which is disclosed in my prior Patent #1,006,213, granted to me upon the 17th day of October 1911.

15 The present invention aims to provide improved means for projecting and retracting the carriage upon which the cutter head is mounted, the frame with which the motor is directly assembled, constituting one of 20 the bearing portions of the carriage.

25 A further object of the invention is to provide an improved construction in which the driving and driven parts are for most part carried by the frame upon which the motor is mounted, the operative security between the parts of the machine being thus increased.

30 Another object of the invention is to provide novel means for operating the conveyer.

35 With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

40 In the accompanying drawings,—Figure 1 shows the invention in top plan, parts being broken away; Fig. 2 is a longitudinal section upon the line A—B of Fig. 1; Fig. 3 is a longitudinal section upon the line C—D of Fig. 1; Fig. 4 is a transverse section upon the line E—F of Fig. 1; Fig. 5 is a section upon the line G—H of Fig. 3; Fig. 6 is a section upon the line K—L of Fig. 1; and Fig. 7 is a sectional detail showing one of the actuating shafts and its attendant parts.

45 In carrying out the invention there is provided a box-like casing 1, preferably of rectangular contour, the casing 1 comprising

side plates 2 and intermediate plates 3, connected adjacent their upper edges by beams 4, the top plate being denoted by the numeral 5 and the bottom plate by the numeral 6. The plates 2 and 3 serve to define a pair of side compartments 7, and the plates 3 define, between them, a central chamber 8. In the front end wall 9 of the casing 1 there is an opening 10, and in the intermediate plates 3, adjacent the front plate 9 there are openings 11. One of these openings 11 is shown in Fig. 3, and at this point it may be stated that the side portions of the machine are like, the side compartments 7 containing duplicate mechanisms. But one of these mechanisms will be described, 70 it being understood without further explanation, and upon an inspection of the drawings, that these mechanisms are of like construction.

Extended longitudinally of the casing 1, 75 upon the bottom 6 of the same, and within the central chamber 8, is a pair of tracks 12 which slant downwardly, toward the front of the machine. Mounted to reciprocate upon the tracks 12 is the carriage of the 80 mining machine, the carriage carrying the cutter head, the construction being such that the cutter head is given both a rotatory and a longitudinally reciprocating motion, when the machine is in operation. 85

The carriage of the mining machine which moves upon the tracks 12, comprises a motor casing 14, the bottom of which is denoted by the numeral 15, the bottom 15 carrying transverse bearings 16, 90 slidably connected with the tracks 12. In the rear wall 17 of the motor casing 14, and in the front wall 18 thereof, is journaled the shaft 19 of the motor 20, which preferably is an electric 95 motor. Secured to the rear end of the armature shaft 19 of the motor 20 is a pinion 21, meshing into a pinion 22, held for rotation with the cutter shaft 23. Across the rear end of the carriage extends a bracket 100 24 in which the rear end of the shaft 23 is journaled. The hub 25 of the pinion 22 is held between the bracket 24 and one of the bearings 16 in which the shaft 23 is journaled. The pinion 22 is thus maintained in 105 mesh at all times with the pinion 21, it being understood that the shaft 23 has a longitudinal sliding movement in the hub 25

of the pinion 22. The shaft 23 may be held in the hub 25 of the pinion 2, for rotation therewith, in any desired manner. In the present instance, there is formed in the shaft 23, a key-way 26, in which are engaged, 5 balls 27 held in a ball socket 28 formed in the inner face of the hub 25 of the pinion 22.

Adjacent its forward end, the shaft 23 is journaled for rotation in a forward bearing 29, having sliding movement upon the tracks 10 12. The motor 20 is effective to cause the bearing 29 to move upon the tracks 12 longitudinally of the machine, and in order that this movement may be transmitted from the 15 bearing 29 to the shaft 23, collars 30 surround and are secured to the shaft 23 in front of, and to the rear of the bearing 29. To the forward end of the shaft 23, and projecting outwardly through the opening 10 20 in the front wall 9, is a cutter head 31, having a spiral rib 31'. The forward end of the cutter head 31 may carry a bit (not shown) of any desired construction.

Secured to the shaft 23 mid-way between 25 its ends, is a worm 32, extending through an opening 33 in the forward portion of the bottom 15 of the motor casing 14. This worm 32 meshes into a gear wheel 34, extended longitudinally of the machine, and 30 projecting through an opening 35 in the inclined hood 36 of the motor casing. The gear wheel 34 is secured to a shaft 37, extended transversely of the machine and journaled for rotation in the forward portion of the 35 motor casing 14. The ends of the shaft 37 enter the side compartments 7, the shaft 37 being adapted to move, together with the motor casing 14, in slots 38 that are fashioned in the intermediate plates 8 of the casing 1, the slots 38 having the same inclination as the tracks 12. The parts of the shaft 37, which lie in the center compartment 8 are equipped with cranks 39, and from this point in the description, but one 45 side of the machine will be described.

Each crank 39 in the shaft 37 is operatively united with a forwardly extending connecting rod 40, pivoted as shown at 41 between ears 42, upstanding from the forward bearing 29 which is adapted to slide upon the tracks 12.

Journaled for rotation in the side compartments 7, adjacent the bottom of the machine, are shafts 43 and 44, carrying 55 sprocket wheels 45, about which is trained a belt conveyer 46, moving above, and cooperating with, an upwardly and rearwardly inclined slide 47 which may be the upper face of one of the beams 4. Journaled for rotation in the side compartment 7 above the shafts 43 and 44 are other shafts 50 48 and 48', carrying sprocket wheels 49, about which is trained a sprocket chain 50.

To the extremity of the shaft 37 which 65 extends transversely of the machine, is se-

cured a sprocket wheel 51. This sprocket wheel 51 is located between the upper and lower runs of the sprocket chain 50. A lever 52 is fulcrumed intermediate its ends upon the shaft 37, the lever 52 carrying at 70 one end segments 53. Upon the upper of these segments 53 there are spaced rollers 54, between which the upper run of the sprocket chain 50 engages. Upon the lower one of the segments 53 there are rollers 55, between which the lower run of the chain 50 engages. Pivotally mounted upon that end of the lever 52 which is remote from the segments 53, is an arm 56. Said arm 56 has a swinging movement upon the lever 52, 75 transversely of the machine. Adjacent its upper end, the arm 56 carries a pair of rollers 57, between which is held for longitudinal sliding movement, and for rotation, but against transverse movement, the crank 80 58 of a shaft 59 journaled for rotation in bearings 60 carried by the side plate 2 of the casing 1. Recalling that there are two of the shafts 59, it will be observed that the rear ends of the shafts extend, as clearly 85 shown in Fig. 1, from the rear end of the casing 1. The rear, protruding ends of the shafts 59 carry cranks 61, operatively united by a connecting rod 62.

The shaft 48' and the shaft 44 carry 90 sprocket wheels 63, about which is trained a sprocket chain 64. The shaft 48' carries a drum 65, about which is engaged a strap 66, constituting a part of a friction brake, the strap 66 being connected with a lever 67, 95 fulcrumed upon any suitable portion of the machine. Recalling that there are two of the levers 67, it will be observed that these levers are connected, through the instrumentality of links 68, with cranks 69, 100 formed upon the ends of a shaft 70, journaled for rotation upon the top of the casing 105.

The numeral 71 may indicate the chain 110 which extends transversely through the casing 1, the chain 71 being anchored at its ends, as denoted by the numeral 72, into any suitable portion of the wall of the mine. Suitable mechanism is provided for operating the chain 71, whereby the casing 1 may 115 be moved transversely, from one side of the opening in which the machine is working, toward the other side thereof. The mechanism for thus moving the machine transversely, constitutes no part of the present invention, and is neither shown nor described 120 in this specification.

The operation of the device as hereinbefore described, is as follows. It will be noted that when the armature shaft 19 of the motor 20 is put into operation, the pinion 21, meshing into the pinion 22, will cause a rotation of the pinion 22, and consequently a rotation of the shaft 23, the rotation of the shaft 23 being imparted to the 125 130

cutter head 31. The cutter head 31 will bore into the face of the mine, and retract the loose material within the casing 1, this material passing through the openings 11, 5 into the side compartments 7, at the forward portions of which, the loose material is removed, by mechanism, the operation of which will be described hereinafter. When the shaft 23 is in operation, the worm 32 will mesh into the pinion 34, causing a rotation of the shaft 37, the cranks 39 of which will operate the connecting rods 40, causing a reciprocation of the forward bearing 29, longitudinally of the machine, the bearing, 10 owing to its connection with the shaft 23 (through the instrumentality of the collars 30) causing a longitudinal reciprocation of the shaft 23, it being recalled that the rear end of the shaft 23 is free to slide to and fro in the hub 25 of the pinion 22. Owing to the fact that the worm 32 is fast upon the shaft 23, it will be seen that the speed with which the shaft 23, and consequently the cutter 21, is retracted, will be greater 15 than the speed with which the shaft 23 and the cutter 31 is projected, since, when the shaft 23 is retracted, the lead of the worm 32 gives an added increment.

From what has been stated hereinbefore, 20 it will be seen that when the motor 20 is in operation, the cutter 31 will be rotated, and will be given a longitudinally reciprocating motion. In addition to this longitudinal reciprocating motion of the cutter 30, when 25 the cutter is in operation, the carriage, comprising the motor casing 14 and the forward bearing 29, may be retracted bodily and advanced bodily, so as to change the position of the cutter 31 with respect to the 30 face of the work, the construction being such that the cutter 31 may, if desired be retracted entirely within the casing 1, when the device is not in use. The mechanism whereby this bodily movement of the carriage is attained, will now be described, in 35 its operation.

Noting Fig. 2 it will be understood that when the periphery of the sprocket wheel 51 which is carried by the end of the shaft 37, is spaced apart from the upper and lower runs of the sprocket chain 50, there will be no operative connection between the shaft 37 and the sprocket chain 50. Let it be supposed that the sprocket wheel 51 is 40 rotated in the direction of the arrow as shown in Fig. 2. Under such circumstances, if the bar 62 be moved longitudinally, the cranks 61 will be operated, causing a rotation of the shaft 59, the crank portion 68 of which will tilt and thrust downwardly the arm 56, the rollers 54 elevating the upper run of the belt 50 out of engagement with the sprocket wheel 51, the rollers 55 elevating 45 the lower run of the belt 50, until the lower run of the belt is brought into engage-

ment with the sprocket wheel 51. If the shaft 70 is rotated, so as to elevate the crank arms 69 and to elevate the links 66, the levers 67 will be elevated, causing the brake straps 66 to engage with the drums 65 which are carried by the shafts 48'. Thus, the sprocket chain 50 will be held against movement. When, therefore, the shaft 37 is rotated, the sprocket wheel 51 being in mesh with the lower run of the belt 50, the carriage, comprising the motor casing 14 and the front bearing 29, will be urged forwardly. It is possible, moreover, as will be readily understood, to swing the lower run of the belt 50 out of engagement with the periphery of the sprocket wheel 51, and to bring the upper run of the belt 50 into engagement with the periphery of the sprocket wheel 51. Under such circumstances, if the shaft 37 be rotated, the carriage, comprising 50 the motor casing 14 and the forward bearing 29 will be retracted. As hereinbefore explained, if the periphery of the sprocket wheel 51 engages neither the upper run nor the lower run of the belt 50, the carriage 55 will remain at rest. Suppose, however, that the sprocket wheel 51 is engaged in the upper run of the belt 50, as shown in Fig. 2, and that the brake strap 66 has been slackened away, so that the shaft 48' may rotate freely. 60 Under such circumstances, when the shaft 37 is put into rotation, the sprocket wheel 51 will operate to drive the chain 50, the chain 50 imparting rotation to the shaft 48', and the shaft 48', through the instrumentality of the sprocket wheels 63 and the sprocket chain 64, causing a rotation of the shaft 44. The shaft 44 will activate the belt conveyer 46, and the material which has 65 passed into the compartments 7, through the openings 11, will be drawn rearwardly by the belt conveyer 48, along the slide 47, the material being ultimately deposited at the rear of the machine.

The mining machine herein disclosed, considered broadly, comprises a casing 1, a carriage 14-29 which is movable upon the casing 1, a cutter shaft 23 which is rotatable in the carriage, driving mechanism, embracing the shaft 37 and sprocket wheel 51, this driving mechanism being operable from the cutter shaft 23, a movable member, represented by the sprocket chain 50, means for holding said member against movement, which means comprises the brake strap 66 and its actuating mechanism, a conveyer 46 adapted to receive material from the cutter shaft 23, means for operatively connecting the movable member with the conveyer, which means embraces the sprocket chain or belt 64 and the parts engaged thereby, and means for operatively connecting the driving mechanism with the movable member, which means includes the lever 52 and its attendant parts.

Having thus described the invention, what is claimed is:

1. In a mining machine, a casing; a carriage 5 slidable upon the casing; a cutter shaft rotatable upon the carriage; driving mechanism operable from the cutter shaft; a movable member; means for holding said member against movement; a conveyer adapted to receive material from the cutter 10 shaft; means for operatively connecting the movable member with the conveyer; means for connecting the driving mechanism with the movable member, whereby the driving mechanism will actuate the movable member and the conveyer, when the holding means is inoperative, and whereby the driving mechanism may slide the carriage, when the holding means is operative.
2. In a mining machine, a casing; a carriage 20 slidable upon the casing; a cutter shaft rotatable upon the carriage; a counter shaft operatively connected with the cutter shaft; a wheel upon the counter shaft; spaced shafts carried by the casing; a flexible element trained about the spaced shafts, the wheel of the counter shaft being located between the runs of the flexible element; means for bringing the runs of the flexible element alternately into connection with the 25 wheel of the counter-shaft; means for holding one of the spaced shafts against rotation; a belt conveyer adapted to receive material from the cutter shaft; and mechanism for operatively connecting the belt conveyer 30 with one of the spaced shafts.
3. In a mining machine, a casing; a carriage slidable upon the casing; a cutter shaft rotatable upon the carriage; a counter-shaft journaled upon the carriage and operatively 35 connected with the cutter shaft; spaced shafts journaled upon the casing; a flexible element trained about the spaced shafts; a wheel upon the counter shaft; means for bringing the flexible element into engagement with the wheel; and means engaging one of the spaced shafts, to hold the flexible element against movement, whereby the engagement between the wheel and the flexible element may serve to slide the carriage.
4. In a mining machine, a casing; spaced 50 shafts journaled for rotation in the casing; a flexible element trained about the shafts; a conveyer; means for operatively connect-

ing the conveyer with one shaft; a carriage mounted to slide in the casing; a cutter 55 shaft mounted upon the carriage; a counter-shaft journaled upon the carriage and having a wheel located between the runs of the flexible element; a lever fulcrumed upon the counter-shaft and having means to engage both 60 runs of the flexible element, to bring the runs alternately into engagement with the wheel; and means for holding one of the first mentioned shafts against rotation.

5. In a mining machine, a casing; spaced 65 shafts journaled for rotation in the casing; a flexible element trained about the shafts; means for holding one shaft against rotation; a belt conveyer operatively connected with one shaft; a carriage mounted to slide 70 in the casing; a cutter upon the carriage, adapted to discharge upon the belt conveyer; a counter-shaft journaled for rotation upon the carriage and having a wheel located between the runs of the flexible element; a lever fulcrumed upon the counter-shaft and having means to engage the runs 75 of the flexible element, to bring the runs alternately into engagement with the wheel; an arm pivotally connected with the lever; 80 and a shaft having a crank portion engaged with the arm.

6. In a mining machine, a track; a motor casing mounted to slide upon the track; the motor including a shaft journaled in the 85 motor casing; a cutter shaft; means for journaling the cutter shaft upon the motor casing; means for connecting the motor shaft and the cutter shaft; a worm fixed upon the cutter shaft; a counter shaft journaled for rotation in the casing and provided with a crank; a gear wheel upon the counter shaft, meshing into the worm; a bearing 90 slidable upon the tracks, the cutter shaft being journaled for rotation in the bearing, but being held against longitudinal movement therein; and a connecting rod 95 united with the bearing and with the crank upon the counter-shaft.

In testimony that I claim the foregoing as 100 my own, I have hereto affixed my signature in the presence of two witnesses.

LOUIS F. HESS.
